UNITED STATES PATENT OFFICE.

ROBERT A. WILSON, OF DALLAS, TEXAS, ASSIGNOR TO GUIBERSON CORPORATION, OF DALLAS, TEXAS, A CORPORATION OF DELAWARE.

WELL PLUG.

Application filed May 6, 1921. Serial No. 467,357.

To all whom it may concern:

Be it known that I, ROBERT A. WILSON, a citizen of the United States, residing at Dallas, in the county of Dallas and State 5 of Texas, have invented certain new and useful Improvements in Well Plugs, of which the following is a specification.

This invention relates to new and useful improvements in well plugs.

10 The invention has particularly to do with a plug or device for providing a water tight seal at the bottom of a well for the purpose of shutting off a flow of water from below and is commonly known as a "bottom water" 15 plug.

The invention is an improvement on the device covered by Letters Patent No. 1,330,430, issued to E. V. Crowell, February 10, 1920. The object of the invention is to 20 provide an improved means for gripping and holding the core when the helical vanes are compressed and to enable the use of a smooth core instead of the grooved core, which is illustrated in the aforesaid patent.

25 A further object is to simplify the construction and manufacture of the device.

A construction designed to carry out the invention will be hereinafter described together with other features of the invention.

30 The invention will be more readily understood from a reading of the following specification and by reference to the accompanying drawings, in which an example of the invention is shown and wherein:

35 Fig. 1 is an elevation of a plug constructed in accordance with my invention and in an expanded and unpacked condition, the well casing being shown in section,

40 Fig. 2 is a vertical sectional detail on an enlarged scale showing the bottom nipple and the improved gripping means,

Fig. 3 is a cross sectional detail on the line 3—3 of Fig. 2,

45 Fig. 4 is an enlarged vertical sectional view of the upper portion of the device, and

Fig. 5 is an underside view of one of the gripping slips.

As is well known, bottom water in a well is very troublesome and interferes with the 50 production of oil by flooding the oil bearing sand. This water is generally under a high pressure and has great erosive power. This condition will become aggravated and more serious unless corrected.

55 In order to properly seal the well to shut

off this objectionable flow of water the bore of the well must be filled completely, with a substantial plug of plastic material capable of hardening and held out against the wall of the well under heavy lateral pressure, so that the bore spaces and variations in diameter of the latter will be thoroughly and closely held.

In the drawings the numeral 10 designates a core of steel or other material, upon 60 the upper end of which is arranged a sleeve 11. The sleeve has a flange 12 into the center of which the core is screw threaded. At its upper end the sleeve is connected to a line of pipe 13 by an ordinary collar 14.

65 Helical vanes 15 have their upper ends bolted to the flange 12 or otherwise suitably attached thereto. At their lower ends the vanes are bolted or otherwise attached to a collar 16 which is internally screw threaded 70 and receives the upper end of a nipple 17. Each vane has sufficient length to extend from the flange 12 to the collar 16 when in its extended position. The core 10 passes axially thru the vanes and telescopes into 75 the nipple 17.

80 At its lower end the nipple is provided with a frusto-conical counter bore 18 in which a plurality of annular wedge shaped slips 19 are arranged. I have illustrated three of such slips, but it is to be understood that the number may be varied. Each slip has its inner vertical face provided with teeth and its outer face inclined at substantially the same angle as that of the counter 85 bore, whereby said slips will freely slide in said counter bore. The outer corner 19' of each slip 19 is slightly reduced so as to obviate a point which would otherwise ride on the surface of the counter bore and possibly score the same. The slips are supported in the counter bore by a retaining ring 20 which is screw threaded in the lower end of the nipple. The lower end of the nipple is externally screw threaded and inserted in the upper end of the usual anchor pipe 21. The core 10 slides thru the slips 19 and the ring 20, and projects into the anchor 21.

90 The part 11 constitutes a head for driving the core downwardly thru the nipple 17. It 105 will be seen that the core is free to move downwardly thru the slips 19, but the relation between the teeth of the slips and the core is such that upon an upward movement of said core, the slips will be carried up- 110

wardly in the counter bore 18, whereby the teeth will bite into the core and hold the same. It is obvious that when the flange 12, which carries the core 10, is moved toward the collar 16 the pitch of the screw formed by the vanes, will be lessened and the aggregate width from the outer edges of the vanes to the center of the core will be increased. Thus the outer edges of the vanes which are sharpened, are caused to bite into the wall of the well opening and to make lateral pressure toward the said wall, thereby digging themselves in and positively gripping the wall of the well.

15 In use the plug arranged as shown in Fig. 1 is lowered into the well, and when in proper position the anchor pipe 21 which may be of suitable length, engages the bottom of the well. The plug is lowered below 20 the casing and the helical vanes do not engage the side walls of the casing, but engage in the wall of the well hole. Tools are used to force the sleeve 11 downwardly toward the ring 20. The core 10 passes thru the slips 25 19 which act to prevent a reverse movement of said core and to hold the vanes in a compressed position. The vanes grip the well wall and after the device is in proper position, cement or other packing may be 30 introduced, as much being added as may be desired. In practice, while lowering the packing material it is advisable to mix ordinary fuel oil with the cement, but this is optional.

35 It will be understood that in the event there is a water bearing stratum below the productive oil stratum, which is separated from the oil stratum by an impervious stratum, and should the impervious stratum be penetrated by the drill, a bottom hole plug would be necessary to prevent the water from invading the oil sand. The anchor pipe 21 not only acts to properly position the plug, but being imbedded in the 40 cement serves to anchor the plug. In ordinary practice the plug will be loaded with cement or packing material and placed in between the vanes before it is lowered, altho it is obvious that this may be done afterward. However, the best results are obtained by lowering the packing with the 45 plug.

50 In order to provide a means for holding a sealing medium in the helical vanes, a number of openings 22 are provided in the edges of the vanes and serve as anchorage for the sealing medium, and thru which wires (not shown) may be run if desired to better hold the sealing medium in place, this

being a common expedient, illustration is 60 not believed necessary. The preferred form of sealing medium is oakum saturated with a thin cement mixture, wrung out about half dry and then tied in the helical vanes, however, it is to be expressly understood that 65 any form of sealing medium may be used and the invention is not to be limited either to a sealing medium or any particular kind of medium. The plug after being loaded with sealing medium and attached to the anchor pipe of proper length, constitutes a 70 complete plug in one direction and is given the power to automatically and promptly position itself in a well and to seal or plug 75 the hole at the point desired.

Particular stress is laid upon the use of the arcuate slips. These slips permit the use of a smooth core which is less expensive than a grooved core and provides a more ample holding surface. Further the adjustment of the core is not limited to the distance between grooves or recesses and it is not necessary to move the core a prescribed distance before the fastening means will 80 take hold. A further advantage is that it is 85 not necessary to provide lateral holes thru the parts and there are no outside movable parts in connection with the fastening means.

Various changes in the size and construction of the parts as well as modifications, 90 may be made without departing from the spirit of the invention.

What I claim, is:

In a well plug, a core having its lower 95 engaging portion smooth, said core being provided at its upper end with a head, a tubular nipple slidably receiving the smooth engaging portion of the core, said tubular nipple having a conical bore at its lower 100 end decreasing in diameter upwardly, the lateral wall of the conical bore being imperforate, the lower end of the tubular nipple being internally and externally threaded, tapered gripping slips mounted in the conical 105 bore and having their inner faces serrated to engage the smooth portion of the core, a removable ring receiving the core and having exterior screw threads to engage the interior screw threads of the tubular nipple, an 110 anchor pipe engaging the exterior screw threads on the lower end of the tubular nipple, and helical vanes surrounding the core and attached to said head and to the upper end of the tubular nipple.

115 In testimony whereof I affix my signature.

ROBERT A. WILSON.
